UNITED STATES PATENT OFFICE

169,486

HAT

Victor T. Hoeflich, Forest Hills, N. Y.

Application September 19, 1952, Serial No. 21,520

Term of patent 14 years

(Cl. D3—13)

To all whom it may concern:

Be it known that I, Victor T. Hoeflich, a citizen of the United States and a resident of Forest Hills, in the county of Queens and State of New York, have invented a new, original, and ornamental Design for a Hat, of which the following is a specification, reference being had to the accompanying drawing, forming a part thereof, wherein:

Fig. 1 is a front elevational view of a hat embodying my new design;

Fig. 2 is a side elevational view thereof;

Fig. 3 is a top plan view; and

Fig. 4 is a bottom plan view.

I claim:

The ornamental design for a hat, substantially as shown.

VICTOR T. HOEFLICH.
